UNITED STATES PATENT OFFICE.

GEORGE C. JEROME, OF CHICAGO, ILLINOIS.

PACKAGING ROD PACKING IN COMBUSTIBLE MATERIAL FOR UNSWEATING THE SAME.

Application filed May 1, 1922. Serial No. 557,536.

To all whom it may concern:

Be it known that I, GEORGE C. JEROME, a citizen of the United States, residing at Chicago, in the county of Cook and State of Illinois, have invented certain new and useful Improvements in Packaging Rod Packing in Combustible Material for Unsweating the Same, of which the following is a specification.

10 My invention relates to packaging metallic packing for piston and valve rods, formed in sections and caused to adhere together as a unitary structure until ready for use, in combustible material which prevents damage 15 to the rod packing during shipment and the complete combustion of which causes the metallic packing to separate into its component parts, without overheating or causing damage or injury to the sections.

20 In the usual practice in the manufacture and fitting of rod packing, the ring is made in two or three pieces for the purpose of obtaining a continuous close fit around the rod. The joints of these sections are formed 25 to feather edges around the rod, and in the event of one of these edges being broken in the slightest degree either in shipment or in handling it before it reaches its destination, or in the fitting of such packing upon the 30 rod, the ring is useless as the steam would blow through between the rod and the inside of the ring where the feather edge was broken off. Before these rings are applied to the rod it is necessary to bore them to 35 the exact size of such rod, and in this handling and boring the feather edges of the sections are very liable to breakage whereupon the ring becomes useless. I cause the sections to adhere together as a unitary structure so 40 that it may be shipped to the railroad or locomotive shop in such unit condition and while in this condition be bored out to the proper size to fit the rod to which it is to be applied. Thereupon, by the application of 45 heat the ring is separated in its component parts, with the feather edges thereof perfectly preserved, thereby overcoming the wastage which occurs in other packing rings due to broken joints or edges.

50 I have found that the ring in its unitary condition must be subjected to sufficient heat to unsweat or cause the ring to separate into its component parts but that excessive heat will spoil or injure the sections, being made 55 of an alloy, usually containing copper, readily affected by excessive heat. When not

enough heat is applied, the solder or other material causing the sections to adhere together is not melted sufficiently to cause the parts to separate and a careless or ignorant 60 shopman will try to force the parts to separate, which might result in breakage of the feather edges of the sections, rendering the packing useless. To overcome these serious difficulties and insure proper and complete 65 separation of the sections without the danger of overheating or injuring the sections, the package in which the rod packing is packed and shipped contains a quantity of fuel which when it is ignited and the packing is 70 subjected to the heat generated by its complete combustion, causes the sections to separate without overheating or injuring the sections. This material, in addition to forming the fuel also constitutes packing or 75 stuffing for the rod packing, the material being stuffed or packed around the packing in the package to serve as a cushion and thereby prevent damage to, or breakage of the rod packing during shipping and handling of the package. I also place in the package draft-sticks, upon which the packing is adapted to be seated when subjected to the heat caused by the combustion of the packing fuel, so that there will be complete 80 and efficient combustion of the fuel.

In the drawings, Fig. 1 is a perspective view showing the packing box, the rod packing, the fuel in which the rod packing is to be packed and the draft sticks; Fig. 2 is a 85 perspective view illustrating the method of causing the rod packing to separate to its component parts, and Fig. 3 is an end view of the packing ring with the sections separated.

The rod packing ring is formed in sections or segments 4 and these sections have feather edges, indicated at 5, which will be next to the rod when applied thereto. Solder is applied to the ends of the sections, the solder preferably being treated with an acid solution, so that the solder will cause the sections to 90 adhere together. The sections therefore constitute practically a unit and can be packed in the package and shipped in such condition. The rod packing is packed in the packing box 6 which is of the proper size and may be of any desired construction and formed of any suitable material. The package also contains the combustible packing material 7, which is preferably but not necessarily waxed excelsior, the excelsior being 95

100

105

110

packed or stuffed all around the rod packing so that the excelsior serves as packing material or a cushion to prevent jarring or breaking of the rod packing during handling and shipping of the box. The excelsior is preferably waxed to increase its heat content. There is just sufficient material 7 to melt the solder and cause the sections to fall apart when the packing is placed over the material and the latter lighted and completely burned and not an excessive amount of material which would result in injury or damage to the sections due to overheating. The box has printed on it specific instructions describing how this operation of unsweating the ring should be carried out. In combination with the rod packing and the combustible material 7 in which it is packed, I include draft sticks 8; preferably three in number, which are of any desired material and of a proper size to permit the proper amount of draft to be supplied to the material 7 when the material is burned to separate the ring into its component parts, as shown in Fig. 2, the ring then resting upon the draft sticks.

From the above description it will be obvious that I pack in a package of suitable size the metallic packing ring and the combustible stuffing material in which it is packed and which may be burned when the ring is on the draft sticks and over the material to cause the ring to separate in its component parts without overheating the sections, the material to be completely burned to insure the separation. It is also apparent, that the unsweating of the packing is greatly expedited or facilitated with consequent saving in time to the workman, who at the time he receives the rod packing to be unsweated, is given the exact amount of fuel for unsweating the packing and in which the packing is shipped.

I claim:

1. In a package, the combination of a metallic packing formed of sections having means for temporarily causing them to adhere together as a unitary structure, and a quantity of fuel adapted to cause the structure to separate into its component parts by complete combustion of the fuel without injury to the packing.

2. In a package, the combination of a me-

tallic packing formed of sections having means for temporarily causing them to adhere together as a unitary structure, a quantity of fuel adapted to cause the structure to separate into its component parts by complete combustion of the fuel without injury to the packing, and draft sticks of the proper size for effecting proper combustion of the fuel.

3. In a package, the combination of a metallic packing formed of sections having means for temporarily causing them to adhere together as a unitary structure, and a quantity of fuel sufficient to hold the structure in place in the package and act as a cushioning means therefor and cause the structure to separate into its component parts by complete combustion of the fuel without injury to the sections.

4. In a package, the combination of a metallic packing formed of sections having means for temporarily causing them to adhere together as a unitary structure, draft sticks of the proper size, and a quantity of fuel sufficient to hold the structure and sticks in place in the package and act as a cushioning means therefor and cause the structure to separate into its component parts by complete combustion of the fuel without injury to the sections.

5. In a package, the combination of a metallic packing formed of sections soldered together to cause them to adhere together to form a unitary structure, material in which the structure is packed, treated with a highly inflammable substance, there being sufficient material, so treated, to melt the solder and cause the sections to fall apart by complete combustion of the material without injury to the sections.

6. In a package, the combination of a metallic packing formed of sections soldered together to cause them to adhere together as a unitary structure, waxed excelsior in which the structure is packed, there being sufficient waxed excelsior to melt the solder and cause the sections to fall apart by complete combustion of the excelsior without injury to the sections, and draft sticks of the proper size to effect proper combustion of the excelsior.

GEORGE C. JEROME.
